Graham Harris
ATTORNEYS

UNITED STATES PATENT OFFICE.

JOSEPH STRAND, OF LOS ANGELES, CALIFORNIA, ASSIGNOR TO KLINCH LATH CORPORATION, A CORPORATION OF CALIFORNIA.

PLASTER BOARD.

Application filed June 25, 1924. Serial No. 722,265.

My present invention is referred to as a strand-key plaster board for the reason that external strands of wire, or the like, are intended to be used, as by securing them to one or both of the faces of plaster board, in the keying of a coat or coats, such as a finishing coat or a protective coat, thereto; and, in a preferred embodiment of my invention, the mentioned strands may serve not only in the keying or anchoring of the mentioned coat or coats, but also in the external reinforcement of the plaster board and in the connecting of plaster boards to one another, or to any foundation or support therefor, such as, for example, the studs of a wall.

Other objects of my invention will appear from the following description of an advantageous embodiment thereof, taken in connection with the appended claims and the accompanying drawings, in which

Fig. 1 is a perspective view of one corner of a plaster board illustrating my invention.

Fig. 2 is a sectional view on an enlarged scale, this view being taken in a plane such as is indicated by the line 2-2 of Fig. 1, and a coating being shown as applied to said plaster board.

Referring to the details of that specific embodiment of my invention chosen for purposes of illustration, 11 may be a substantially flat body formed of plastic material of any usual or preferred character and provided with a layer or layers of fibrous material, such as the sheets 12, 12' of a suitable paper, one or both surfaces of any suitable board being preferably provided with integral keying means such as the slots 13, 13', shown as arranged with their longitudinal axes extending in two directions substantially at right angles to one another and parallel with the edges of a substantially rectangular slab of plaster board.

It will be understood that slots of the character shown, or of any preferred character, although serving a useful purpose in the keying of an additional coat or coats to a plaster board, are liable appreciably to weaken the same. To offset, or to more than offset this weakening, and to aid in the keying of a coat or coats to a plaster board, I accordingly provide, on one or both surfaces of my novel plaster board, strands of a reinforcing material such as wire; and these

strands are preferably arranged transversely and centrally of the respective slots, regardless of the depth and configuration of the same, in such manner as to assure the secure retention of the key projections extending from any coat applied thereto. For example, I may employ only strands such as the wires 14, shown as extending in a horizontal direction across the slots 13, and preferably provided with free projecting ends 15; or I may substitute therefor or associate therewith strands 16, having projecting ends 17, and extending across the slots 13'. If the circumstances of use are deemed to justify unusual precautions with a view to adequate reinforcement or keying with a coating, I may optionally employ additional strands, extending in any desired direction, such as the strands 18, having the free ends 19, these strands being shown as intersecting the strands 14 above each of the slots 13. Instead of employing straight strands, I may optionally form any desired loops therein, the points of depression between such loops being shown as secured by suitable means, such as staples 20, shown as extending through both of the fibrous layers 12, 12' and as clinched beneath the lower fibrous layer in such manner as to permit an optional painting or papering directly thereon, as may be desired in, for example, the construction of inexpensive cabins, or the like.

The free ends 15, 17, or 19, when such ends are provided, projecting beyond the edges of the slab proper, may be used in the connecting of one slab to another, and in the securing of slabs to studs or other supporting members as best shown in Fig. 2, in which the use of long staples 21 instead of or together with ordinary nails 22 is suggested.

Although I have herein described one complete embodiment of my invention, it will be understood that various features thereof might be independently employed and also that various modifications might be made by those skilled in the art, without the slightest departure from the spirit and scope of my invention, as the same is indicated above and in the following claims.

I claim as my invention:

1. A plaster board provided with longitudinal and transverse keying slots having

- sides substantially at right angles to the surface of said board; and a plurality of plaster reinforcing wires secured to the sides of, and entirely outside of, said plaster board, and arranged criss-cross over a portion of said slots.
2. A plaster board comprising: a slab having slots with sides substantially at right angles to the surface of said slab; and 10 plaster retaining means comprising strands of wire secured to a face of said plaster board and extending across said slots, said wires engaging the surface of the plaster board only at points where secured thereto.
- 15 3. A plaster board comprising: a slab having slots with sides substantially at right angles to the surface of said slab; and plaster retaining means comprising strands of wire secured to a face of said plaster 20 board, said strands extending in a plurality of directions and engaging the surface of the plaster board only at points where secured thereto.
4. A plaster board comprising: a slab 25 composed of fibrous layers and having slots adapted to cooperate in the retention of a coating applied thereto; and cooperating coating retaining means comprising metallic strands secured to a face of said plaster 30 board extending in a plurality of directions across said slots to aid in the retention of key projections therein, said strands engag-
- ing said plaster board only adjacent points where secured thereto.
5. A plaster board comprising: a slab 35 composed of fibrous layers and having slots adapted to cooperate in the retention of a coating applied thereto; cooperating coating retaining means comprising metallic strands secured to a face of said plaster 40 board extending in a plurality of directions across said slots to aid in the retention of key projections therein, said strands engaging said plaster board only adjacent points where secured thereto; and staple securing 45 means for securing said strands to said plaster board.
6. A plaster board comprising: a slab formed of a cementitious substance compressed between sheets of fibrous material, 50 said slab having a plurality of elongated depressions in one face thereof, said depressions extending some parallel to and some at right angles to the edge of said slab; a plurality of wire strands secured to the face 55 of said slab and bridging said depressions, whereby plaster, when applied, will fill said depressions and entirely enclose said strands at all points thereof, except where said wires are secured to said slab.

In testimony whereof, I have hereunto set my hand at Los Angeles, California, this 12th day of June, 1924.

JOSEPH STRAND.

CERTIFICATE OF CORRECTION.

Patent No. 1,664,837.

Granted April 3, 1928, to

JOSEPH STRAND.

It is hereby certified that error appears in the printed specification of the above numbered patent requiring correction as follows: Page 2, line 54, claim 6, following the semi-colon after the word "slab" insert the words "plaster retaining means comprising"; and that the said Letters Patent should be read with this correction therein that the same may conform to the record of the case in the Patent Office.

Signed and sealed this 8th day of May, A. D. 1928.
